US00D693071S

(12) **United States Design Patent**
Dammkoehler

(10) **Patent No.:** **US D693,071 S**
(45) **Date of Patent:** **** Nov. 5, 2013**

(54) **FLOOR CLEANING MACHINE**

(75) Inventor: **Denis Dammkoehler**, Backnang (DE)

(73) Assignee: **Alfred Kaercher GmbH & Co. KG**,
Winnenden (DE)

(**) Term: **14 Years**

(21) Appl. No.: **29/374,322**

(22) Filed: **Jul. 27, 2011**

(30) **Foreign Application Priority Data**

Feb. 11, 2011 (WO) DM/075 355

(51) **LOC (9) Cl.** **15-05**

(52) **U.S. Cl.**

USPC **D32/16**

(58) **Field of Classification Search**

USPC D32/1, 4, 15-16, 19-20; 15/49.1, 50.1,
15/50.3, 52.1, 320-321, 323, 340.1, 340.3,
15/340.5; 134/115 R

(57) **CLAIM**

The ornamental design for a floor cleaning machine, as shown
and described.

DESCRIPTION

FIG. 1 is a front, top and right side perspective view of a floor
cleaning machine showing my new design;

FIG. 2 is a front, top and left side perspective view showing
the design;

FIG. 3 is a front elevational view of the design;

FIG. 4 is a right side elevational view of the design;

FIG. 5 is a left side elevational view of the design; and,

FIG. 6 is a top plan view of the design.

The broken line showing of various elements in the drawings
forms no part of the claimed design.

1 Claim, 6 Drawing Sheets
